DESIGN FOR A SHOPPING BAG

Henri Lebaigue, Pelham, N. Y., assignor to Cartier, Inc., New York, N. Y., a corporation of New York

Application February 11, 1943, Serial No. 109,529

Term of patent 7 years

To all whom it may concern:

Be it known that I, Henri Lebaigue, a citizen of the United States of America, residing at Pelham, in the county of Westchester and State of New York, have invented a new, original, and ornamental Design for a Shopping Bag, of which the following is a specification, reference being had to the accompanying drawing, forming part thereof.

The figure is a perspective view of a shopping bag, showing my new design.

The rear of the bag is substantially plain.

I claim:

The ornamental design for a shopping bag, as shown and described.

HENRI LEBAIGUE.
